In Great Britain January 31, 1944

5 Claims. (Cl. 15—317)

1

This invention relates to apparatus for cleaning boiler tubes and the like, commonly termed "soft blowers," of the kind employing a steam ejector which is mounted for reciprocation within a steam chest to assume its operative or inoperative position under the control of an operating mechanism comprising a screwed spindle cooperating with a nut and which steam ejector is also required to be rotated to cause the steam nozzle, or nozzles, to traverse the required tube area. Although steam is referred to as constituting the cleansing medium it is understood that any other suitable fluid can be substituted therefor.

The invention has for its object to provide a modified and improved and more efficient construction of such operating mechanism.

In the accompanying drawings:

Figure 1 is a longitudinal section of one form of apparatus incorporating the invention,

Figure 2 is a vertical section on the line 2—2, Figure 1 taken in the direction of the arrow with the casing removed,

Figure 2a is a fragmentary top plan view of one end of the piston 15 with parts removed,

Figures 3, 4 and 5 are diagrammatic views showing essential parts of the coupling according to the invention shaded in accordance with the Heraldic convention and in their different operative positions,

Figure 6 is a longitudinal section similar to Figure 1 but of a modified form of the invention, and

Figure 7 is a detail view showing the piston 15 of Figure 6 as seen from below that figure.

In carrying the invention into effect in one convenient manner as illustrated in the drawings, and referring first to Figures 1 and 2, a tube cleaning apparatus or soot blower is provided comprising a steam chest 1, in the form of a tubular casing, to the inner end of which there is secured, as by screw-threading 2, a valve seat 3 of ring formation and beyond which a tubular extension 4 of the steam chest is provided and secured, as by screw-threading 5, to a steam branch 6 in turn jointed at 7 to the steam chest by means, for example, of studs 8.

The steam ejector 9 is accommodated within the tubular extension 4 of the steam chest and is in the form of a hollow piston having openings 10 at its outer end, through which steam is passed to the piston interior, and a nozzle 11 at its inner end, through which the steam issues and impinges against the tubes to be cleaned. The ejector piston is connected by a tie pin 12 with

2

a block 13 forming the movable valve part of a simple shut-down valve, the fixed seat of which is the seat 3 referred to and which movable valve part 13 is in turn connected by another and 5 screwed tie pin 14 with a piston 15 mounted for movement within the steam chest 1.

To facilitate the removal of the interior of the apparatus it is only necessary to break the one joint 7 by removal of the nuts 8a from the 10 studs 8. This permits the steam chest and with it the entire interior thereof, including the valve seat, movable shut-down (or alternatively a piston) valve member and the steam ejector, being removed.

15 In connection with the apparatus as just described, operating mechanism is required to produce the required movements of the steam ejector such that the same may be moved axially to open the valve and then rotated to cause the steam 20 nozzle to traverse the required tube area and the construction of this operating mechanism is preferably such that the first part of the movement of the ejector into the steam projecting or operative position takes place in a straight 25 line or non-rotary manner during which time the valve is fully opened, and is followed by a purely rotary movement of the ejector, at which time the ejector will be receiving a full supply of steam, due to the fully open position of the valve.

30 On the reverse or retracting movement of the ejector this sequence of movements must take place in the reverse order so that the ejector is first given a purely rotary motion to restore the steam nozzle to its zero position and then the 35 ejector is moved axially to fully close the valve.

The operating mechanism for producing the 40 above sequence of movements of the steam ejector comprises essentially a screwed spindle 16 and a nut 17 but the connection of the two is such that the nut may be held stationary and the 45 screwed spindle made to travel through the nut (when axial movement of the ejector results) or the nut may be freed to rotate with the screwed spindle (when a rotary movement of the steam 50 ejector results) and the operating mechanism provided by this invention incorporates a mechanical coupling by which this change of the operative conditions between the nut and screwed spindle may take place automatically during the rotation of the screwed spindle and without the need for any conscious effort on the part of the operator, in the case of a hand controlled soot blower installation.

Referring now to this operating mechanism, 55 at its outer end, remote from the valve 3, 13, the

piston 15 is formed with a slot which is of T-section and is open at the outer end of the leg 22 of the T to receive therein a pair of diametrically opposite fingers 23 which project axially from the inner end of the nut 17 so as to lie in the path of the side walls 22a of the leg of the T-slot, and which nut has an internally threaded central bore 17x through which the screwed spindle 16 passes. The latter terminates at its inner end in a flanged disc 28 which is accommodated in the cross slot or top 27 of the T. The screwed spindle 16 is centrally disposed within the outer end of the steam chest to extend longitudinally therein and be co-axial with the piston and steam ejector, and at its outer end the screwed spindle is fitted with a radially projecting stud 32 which engages in an axial groove 33 in the hub 36 of a hand-wheel 37 by which the screwed spindle is rotated, and which stud and groove provide a splined connection which permits the screwed spindle to travel axially through the nut when the latter is restrained against rotation. The central bore or hub of the hand-wheel is extended forwardly towards the steam chest in the form of a co-axial sleeve 38 which fits within the outer end of the steam chest and has on its outer surface an annular circumferential groove 40 in which the inner ends 41a of set screws or studs 41 engage to prevent endwise or axial movement of the hand-wheel, the said studs being screwed through holes in the outer end of the steam chest and being conveniently provided with rotatable rings 41b constituting rollers which engage with the outer periphery 17a of the nut 17 and serve to take the endwise loads.

With the operating mechanism as thus constructed the screwed spindle 16 is connected with the nozzle through the medium of the disk 28 engaging in the recess 27 in the piston and the nozzle can have rotary movement imparted thereto or be restrained against rotation without altering the connection of the screwed spindle with the nozzle. The nut 17 is also connected with the nozzle through the medium of the fingers 23 engaging in the slots 22 on the piston such that at the appropriate moment, and when the nut is forced to rotate, the nut may operate to rotate the nozzle without its operative connection with the nozzle being altered.

The operating mechanism provided in accordance with this invention besides providing these connections of the screwed spindle and nut with the nozzle also incorporates, as above mentioned, a mechanical coupling which is operable automatically during the rotation of the screwed spindle to provide positive coupling conditions when the nut is either restrained against rotation with the spindle by being coupled to a fixed part or is freed to rotate therewith by being coupled to the hand-wheel.

To this end the operating mechanism provided in accordance with the present invention involves the provision, on the nut, of a coupling element which is carried by the nut so as always to be in engagement therewith but which is capable automatically of assuming one or the other of two operative or coupling positions in which, while still retained upon the nut, a portion of the coupling element protrudes from one side of the nut and engages either in a recess in the fixed part or in a recess in a rotary part constituted by the said hand-wheel. In one such position this coupling element, which is shown in the specific examples illustrated as consisting of a ball 42, of hardened steel for example, accommodated

in a hole 42a which extends transversely through a radial flange portion 17b of the nut, positively couples the nut with a fixed casing part constituted by a flange 44 of the steam chest 1 while in its other position the ball 42 positively couples the nut with the hand-wheel 37. To this end the said hole 42a in the nut is open to both faces of the said flange 17b and the diameter of the ball exceeds the depth of the hole so that while the major portion of the ball remains in the hole a portion of the ball may protrude from one side of the flange and engages either in a recess 43 in the fixed casing part 44 or in a recess 45 in the hand-wheel. Also each recess is provided upon otherwise plain surfaces of their respective parts and with which plain surfaces the flange portion 17b of the nut has rotary engagement whereby, in either coupled position of the ball, the latter is firmly held between the particular recess in which it has engaged and the opposite plain surface. Thus the recess 43 is provided upon a plain surface 46 constituting the inner wall of the said flange 44 of the fixed casing and the recess 45 is provided in the plain annular and inner end surface 47 of the hub 38 of the hand-wheel.

The first such above-mentioned position is that which the ball normally occupies, i. e. when the valve 3, 13 is closed and the steam ejector is in the fully retracted position as shown in Figure 1 and with the coupling thus made the nut is restrained from rotating but the screwed spindle 16 is free to rotate through the nut. Such movement is purely axial and is possible due to the spline-like connections afforded by the parts 32, 33 on the one hand and the parts 22, 23 on the other and the axial movement is sufficient fully to unseat the valve member 13 and provide for a full supply of steam to the steam nozzle 11. At this moment it is desired that the steam ejector should be rotated and this takes place automatically when an abutment pin 49 on the hand-wheel is brought up against and made to cooperate with an abutment pin 48 on the nut, the two pins being disposed upon their respective parts to lie in the path of one another and such that when the valve 13 is fully seated they (the pins) are nearly diametrically opposite one another. The mechanism also involves the provision of a fixed pin 50 on the casing part 1 which protrudes into the path of a radial pin 51 on the outer periphery of the nut 17 and which pin 51 (which, of course, is rotatable with the nut) in the normal or starting position of the parts lies against one side of the fixed pin 50.

With the mechanism thus far described it is possible to refer to Figures 3, 4 and 5 to understand the operation of the coupling.

Referring to Figure 3, which represents the starting position of the parts, that is when the steam ejector is fully retracted and the shut down valve 3, 13 is fully seated, in this position the ball 42 is in engagement with its retaining hole 42a in the nut 17 and protrudes also into the recess 43 in the flange 44 of the fixed casing part 1 where it is held fast by being locked between the recess 43 and the opposite plain surface 47 on the hub of the hand-wheel, so that the nut is now positively held against rotation and consequently rotation of the steam ejector is also prevented. On rotation of the hand-wheel in a clockwise direction the recess 45 thereon will, after a half revolution, be brought opposite the ball 42 as seen in Figure 4 and at this point also the pin 49 on the hand-wheel will have made half

a revolution and will be brought up against the pin 48 on the nut. Also at the termination of this half revolution of the hand-wheel and parts just described the screwed spindle 16 will (and permitted by its splined connection 32, 33 with the hand-wheel) have made one half of a complete turn through the stationary nut which will, in the case of the embodiment of the invention according to Figure 1, have produced a purely axial movement of the movable valve part 13 of an extent sufficient fully to open the valve.

In the intermediate position of the parts therefore, as seen in Figure 4, the valve will be fully open and the coupling between the nut and the fixed part will still be effective. In other words, the ball 42 will still be engaged in the recess 43 in the fixed part although the other recess 45 is now opposite it, but continued rotation of the hand-wheel in a clockwise direction will now cause the pin 49 on the hand-wheel to press against the pin 48 on the nut and thereby constrain the nut to rotate, the immediate effect of which will be to cause the ball 42 to be shifted positively sideways or axially into engagement with the recess 45 in the hand-wheel so that as, during continued rotation, the ball is moved away from the fixed recess 43 and the ball becomes locked between the other recess 45 and the plain fixed surface 46, a positive coupling is made between the nut and the hand-wheel and this coupling cannot be broken until the motion of the hand-wheel has been reversed and the ball brought back again to lie opposite the recess 43 in the fixed casing part.

Continued rotation of the hand-wheel in a clockwise direction from the position of the parts, as seen in Figure 4 but with the coupling effective as between the nut and the hand-wheel, will take place until the pin 51 on the outer periphery of the nut is brought up against the fixed pin 50 when further rotation of the hand-wheel in a clockwise direction is arrested and this after the hand-wheel has made somewhat less than one complete rotation, thereby ensuring that the recess 43 in the fixed casing part 44 is not brought opposite the ball (still coupled with the hand-wheel) at this time. The position of the parts at this stage is shown in Figure 5 and compared with the position as shown in Figure 4 the effect of moving the parts from the one position to the other will have caused the steam nozzle 11, by the rotation of the nut and the engagement of its fingers 23 with the sides of the slot 22, to have partaken of a purely rotary motion in a clockwise direction which will be sufficient to cause the steam nozzle, in its now projected position, to traverse the required tube area but which rotary motion will be less than 360° due to the engagement of the pin 51 on the outer periphery of the nut with the fixed pin 50.

As stated, with the position of the parts as illustrated in Figure 5, the engagement of the pin 51 on the nut with the fixed pin 50 prevents further rotational movement of the hand-wheel in a clockwise direction and the parts therefore are now ready to be returned to their original position as shown in Figure 3 by rotation of the hand-wheel in the opposite direction, that is, anti-clockwise. It will be observed that during the last part of the clockwise rotation of the parts from the position shown in Figure 4 to that shown in Figure 5, the clockwise rotation of the nut is imparted both by the engagement of the pins 48 and 49 as well as by the positive cou-

pling of the nut to the hand-wheel by the ball 42. On reversing the direction of rotation, that is, by rotating the hand-wheel anti-clockwise, the pins 48 and 49 (which constitute a one-way drive) are no longer effective to rotate the nut, but their relative positions continue to remain the same due to the fact that the ball 42 still functions to lock the nut positively to the hand-wheel and it is this positive lock which serves to cause the anti-clockwise rotation of the hand-wheel to be imparted to the nut, which continues until the pin 51 on the nut is brought up against the right hand side of the fixed pin 50 corresponding to the starting position, as shown in Figure 3. In this position the steam nozzle will have been rotated back to its zero or starting position and the ball (still engaged in the recess 45 in the hand-wheel) will be located opposite the recess 43 in the fixed casing part. That is to say the ball and two recesses will now all be in line with each other. The nut is now held against further rotation anti-clockwise but the hand-wheel is still free to turn anti-clockwise and must have its motion in this direction continued as the steam nozzle, although in its zero position, considered circumferentially, is still in its axially projected position and the valve 3, 13 is therefore still open and further rotation of the hand-wheel anti-clockwise is therefore necessary in order to retract the nozzle and seat (or fully close) the valve. Such further rotation of the hand-wheel anti-clockwise will however be accompanied by a lateral and positive shifting of the ball 42 from its coupling engagement with the recess 45 in the hand-wheel into its other coupling position in which it protrudes into the fixed recess 43. The hand-wheel 37 is therefore again freed from rotation with the nut and during the last half revolution anti-clockwise is able to rotate the screwed spindle relatively to the nut and cause the spindle to be retracted through the nut and draw along with it the piston 15 and the steam ejector and associated parts until the movable valve part 13 is seated firmly upon its seat 3; when this occurs further rotation of the hand-wheel anti-clockwise will be arrested and the parts will be restored to their original positions as shown in Figure 3, the ball 42 being still in coupling engagement with the fixed recess 43 and the recess 45 in the hand-wheel being now diametrically opposite the ball.

The embodiment of the invention as illustrated in Figure 1 is suitable for use when merely a part (in this case one half) of a complete turn of the hand-wheel is sufficient fully to open the valve 3, 13. If a longer axial movement of the steam ejector is required such that more than one complete rotation of the screwed spindle must take place before the required axial movement is obtained a modification of the invention is necessary and such a modification is illustrated in Figure 6 wherein the parts thereof corresponding to the same parts in Figure 1 are given the same reference numerals.

The essential difference between the construction of the apparatus according to Figure 6 and that according to Figure 1 resides in the provision of the piston with an axial slot 52 in which the fixed pin 50 normally (that is in the closed position of the valve) engages, and in forming the piston with a reduced portion which provides an annular space 53 surrounding this portion of the piston and to which space the axial slot 52 is open at one end. Also the pins 48 and 49 on the nut and hand-wheel respec-

tively, as shown in Figure 1, are replaced in the modification according to Figure 6 by a pin 54 suitably located on the screwed spindle in contact with or in close proximity to the last turn of the thread on said spindle and a radial shoulder or abutment 55 provided by removing a short length of the thread on the nut 17 at its lead-in, whereby the pin 54 will abut against the shoulder 55 at the appropriate moment during the rotation of the screwed spindle. That is to say, only when the screwed spindle has been advanced sufficiently to cause the pin 54 thereon to be brought up against this abutment 55 on the nut will the latter be constrained to rotate and the arrangement (which forms a one-way drive) is such that at this moment the fixed pin 50 (which was previously engaged in the axial slot 52 in the piston and prevented rotation of the piston and hence of the steam ejector) will be located opposite the annular groove 53 so that rotation of the nut is permitted to take place due to the change over of the coupling position of the ball 42 which, as in the previous embodiment, will normally couple the nut 17 to the fixed casing. Thus normally, that is when the valve is closed and the steam ejector retracted, the ball 42 will protrude into the recess 43 in the fixed casing part 44 and although during each complete rotation of the hand-wheel 37 the other recess 45 will be brought opposite the ball, the latter will retain its coupling engagement with the fixed recess 43 until the time arrives when not only will the recess 45 be opposite the ball but the pin 54 will be brought up against the abutment 55.

The operation of the mechanism illustrated in Figure 6 is as follows:

With the valve 13 closed against its seat 3 and with the parts otherwise as illustrated in the figure, upon the hand-wheel 37 being rotated clockwise, the screwed spindle will be rotated through the nut (which is now held stationary by the ball 42 coupling the nut to the fixed casing part 44) and produce a purely axial movement of the steam ejector so long as the fixed pin 50 remains in engagement with the axial slot 52 in the piston and the arrangement is such that when the second last turn of the hand-wheel 37 is reached the fixed pin 50 leaves the axial groove 52 and enters the circular or annular groove 53 at the same time as the pin 54 on the screwed spindle is brought up against the screw-thread end or abutment 55. Consequently continued rotation of the hand-wheel clockwise will cause the ball 42 to be shifted sideways in its hole 42a in the nut so that it now protrudes into the aligned recess 45 on the hand-wheel and accordingly the nut is now constrained to rotate with the hand-wheel. Continued rotation of the hand-wheel clockwise for another complete revolution will cause a radial stop 56 on the reduced piston portion to be brought up against the fixed pin 50 (this corresponding to the position of the pin 51 with the pin 50 as seen in Figure 5) and further rotation of the hand-wheel clockwise will then be arrested. Upon rotating the hand-wheel anti-clockwise the pin 54 on the screwed spindle ceases to function but the ball remains locked in position between the hand-wheel and the nut until the ball is brought opposite to the recess 43 in the fixed casing part. When this occurs further rotation of the hand-wheel anti-clockwise will cause the ball to be pushed sideways again in its hole 42a in the nut and into en-

gagement with the recess 43, because at that time the fixed pin 50 will have again come up against the radial stop 56 on the reduced piston portion where the fixed pin 50 will be aligned with the axial slot 52 in the piston. Continued rotation of the hand-wheel, therefore, clockwise will then cause the screwed spindle to be retracted through the nut and produce a purely axial retracting movement of the steam ejector by the engagement of the fixed pin 50 with the axial slot 52 until the movable valve member 13 has been fully seated against its seat 3 when further rotation of the hand-wheel anti-clockwise will be arrested.

In both modifications of the invention according to Figures 1 and 6 the ball 42 provides a definite mechanical lock between the nut and the operating handle (the rotary part) when once the ball has been engaged in the recess in the hand-wheel and such lock cannot be broken until the hand-wheel has been rotated backwards to bring these parts into their original position.

The recesses 43 and 45 are preferably made to have a V-shape section as shown which facilitates their production by a simple boring operation and also provides for the obtaining of the required frictional engagement of the protruding ball portion with either recess but the recess is not necessarily limited to such shape.

The piston 15 is formed at its inner end with an end face 15a which is presented to the steam admitted to the steam chest through the steam inlet 18, via a bore 6a in the steam branch 6, and if the area of the end face is greater than that of the inner end surface of the shut-down valve or of the ejector at the opposite end of the steam chest there will be a rearward loading of the piston by the steam, with respect to the direction of flow of the steam to the ejector, and as a consequence the piston will tend to be maintained in close frictional engagement with the disc 28 at the inner end of the screwed spindle 16.

The steam branch 6 has the bore 6a through which the steam from the main steam supply pipe flows to the steam chest and another bore 6b in which the forward end of the steam chest is received and both bores terminate at a common end surface 19 of the steam chest, whereby it is possible to effect a steam-tight joint with the corresponding end surface 20 of the steam chest by the single jointing member 7, which is disposed in one and the same plane. The arrangement permits of the use of the fixed valve seat 3 in rear of the steam inlet 18, having regard to the direction of flow of the steam, while permitting of the interior of the apparatus being withdrawn without the necessity of breaking the steam joint between the end surface 21 of the steam branch and the main steam supply pipe.

In either modification of the invention provision is made for the escape of any steam which may pass to the rear of the piston and this without the disadvantages of such steam upsetting the piston balance. To this end in Figure 1 the steam chest is provided with a steam vent 56 while in Figure 5 the fixed pin 52 has a hollow bore 57 which acts as a steam vent.

While it is intended that the ball should be shiftable bodily within its hole in the nut so that a portion of the ball may protrude from one or the opposite face of the nut it may be preferable to provide slight reductions of the hole at the ends thereof, sufficient to prevent

the ball from falling out of the hole when the operating mechanism is dismantled, yet such as will not prevent the required shifting movement from taking place.

We claim:

1. Apparatus for cleaning boiler tubes in combination a casing, an ejector nozzle mounted in said casing for axial movement for projection therefrom, and for rotational movement about its axis for traversing fluid discharged from said nozzle, and means for projecting and rotating said nozzle consisting of a rotatably mounted screw-threaded actuating member connected to said nozzle by means which permits rotation relatively thereto and prevents relative axial movement of nozzle and actuating member, a nut engaging said actuating member, means connecting said nut and said nozzle which permits axial movement of said nozzle relative to said nut and prevents relative rotation of said nut and said nozzle, means normally locking said nut to said casing, means responsive to the relative rotary positions of said actuating member and said nut to release said nut from said casing and to lock said nut to said actuating member whereby initial rotation of said actuating member rotates said member relative to said nut to project said nozzle axially until said nut is released from said casing and is locked to said actuating member, whereupon continued rotation of said actuating member rotates said nut, and said nozzle driven thereby, and arrests further axial movement of said nozzle.

2. Apparatus as claimed in claim 1, wherein the locking means comprises a ball retained and moveable longitudinally in a transverse bore in the nut, that portion of the nut containing the ball being rotatable in engagement on one side face thereof with an interior surface of the casing, and a manually operable member with an end face with which the other side face of said nut is in rotatable engagement, said manually operable member being mounted for rotation in the casing and having splined connection with said actuating member for operation thereof, and the casing and said manually operable member having a recess into which a portion of said ball can protrude from said bore in the nut, respectively, for locking the nut to the casing and the nut to said actuating member.

3. Apparatus as claimed in claim 2, wherein the nut and the manually rotatable member are provided with abutments on the nut and the

manually rotatable member, respectively, which come into contact with one another when the actuating member has been turned a predetermined amount in one direction by rotation of the manually rotatable member, and stop means is provided to arrest the rotary movement of the nut subsequent to further rotation of the manually rotatable member in said direction.

4. Apparatus as claimed in claim 3, wherein 10 said stop means consists of a pin secured to the casing, and a piston secured to the ejector nozzle and having a composite slot or groove in which said pin engages, which composite slot comprises an axially extending portion and an annular portion, the latter having an abutment with which the pin contacts to arrest the nut during said further rotation of the manually rotatable member.

5. In combination, a fixed part, a rotatable part, 20 a rotatable threaded spindle, a driving connection between said rotatable part and said spindle, a nut threaded on said spindle, said nut being formed to provide a carrier portion, a locking element movable in said carrier portion 25 to protrude into a recess in said fixed part to lock said nut from rotation with said spindle, and protrude in a second position into a recess in said rotatable part to release said nut and lock said nut to said spindle for rotation therewith, said fixed part and said rotatable part 30 having cammed surfaces, respectively, which during rotation of said spindle force said locking element into said position to positively lock said nut to said fixed part in one position and 35 to said rotatable part in said second position.
